(57) **CLAIM**

I claim the ornamental design for the multi-purpose smart jar, as shown and described.

DESCRIPTION

The multi-purpose smart jar is a versatile storage device that is comprised of a top portion of a jar, a bottom portion of a jar, and a screw top lid. The multi-purpose smart jar is used for, but not limited to peanut butter, jelly, jam, and mayonnaise.

FIG. 1 is a perspective view of an assembled multi-purpose smart jar showing the top portion of the jar, the bottom portion of the jar, and a screw top lid connected in a closed position showing my new design;

FIG. 2 is a perspective view of an assembled multi-purpose smart jar showing the screw top lid connected to the bottom portion of the jar in a closed position;

FIG. 3 is an exploded perspective view of a disassembled multi-purpose smart jar showing the top portion of the jar, the bottom portion of the jar, and the screw top lid;

FIG. 4 is an exploded front view of a disassembled multi-purpose smart jar showing the top portion of the jar, the bottom portion of the jar, and the screw top lid;

FIG. 5 is an exploded back view thereof;

FIG. 6 is an exploded side view thereof;

FIG. 7 is an exploded opposite side view of FIG. 6 thereof;

FIG. 8 is an exploded top view of a disassembled multi-purpose smart jar showing the top portion of the jar, the bottom portion of the jar, and the screw top lid; and,

FIG. 9 is an exploded bottom view thereof.
